UNITED STATES PATENT OFFICE.

EDGAR W. SUMMERS, OF PITTSBURGH, PENNSYLVANIA; PATIENCE C. SUMMERS
EXECUTRIX OF SAID EDGAR W. SUMMERS, DECEASED.

RAILWAY TRUCK.

Application filed May 9, 1921. Serial No. 468,009.

To all whom it may concern:

Be it known that I, EDGAR W. SUMMERS, a citizen of the United States, and a resident of Pittsburgh, in the county of Allegheny and State of Pennsylvania, have invented a new and useful Improvement in Railway Trucks, of which the following is a specification.

The invention relates to railway car trucks, and has particularly to do with the axle journal, journal bearing, journal box, and the portion of the truck frame resting upon the journal box.

As at present manufactured and used, the above mentioned parts of railway car trucks are standardized to accommodate a single form of journal bearing known as the M. C. B. (Master Car Builders') journal bearing, which rests upon the axle journal, and upon which the journal box is indirectly supported. The ends of the journal bearing form thrust bearing faces which cooperate with the flanges of the axle journal to resist lateral movements of the car due both to the irregularity of tracks and to the centrifugal force of a car passing around a curve.

In use, the standard bearings wear away to such an extent that they must be replaced, wear being most rapid at the ends of the bearings because they are of insufficient area to properly distribute the lateral thrust of a car upon the axle flanges. The concentration of lateral thrust upon the small end or thrust bearing faces prevents, to a large extent, the maintaining of a proper film of lubrication between the cooperating axle and bearing thrust faces, and the insufficiently lubricated faces are cut away much more rapidly than if adequate lubrication were possible.

To facilitate the removal and replacement of a standard journal bearing, a block, known as a wedge, is placed between the journal bearing and journal box. To remove a bearing, the box is jacked or otherwise moved upwardly in parallel relation to the axle until pressure is relieved from the wedge. Thereafter, the wedge is removed, the bearing raised from the journal to such height that its outer thrust bearing face is free from the journal flange, and the bearing then moved outwardly through the opening in the journal box. It is largely

because the several parts of the truck are 55 constructed to permit only of this manner of removing and replacing journal bearings that the end thrust faces of the bearing are of insufficient area to properly resist wear.

The primary object of this invention is to 60 so construct certain of the above named parts of railway car trucks that bearings having much larger end thrust faces may be used and be readily replaced either by bearings having enlarged end thrust faces 65 or by standard bearings.

A further object is to provide a journal box the outer end of which may be elevated to remove the bearing.

The invention is illustrated in the accompanying sheets of drawings of which Fig. 1 is a vertical longitudinal central sectional view through the car axle, journal bearing, journal box, and outer end of the truck frame, the plane of view being indicated by the line I—I, Fig. 2; Fig. 2 a transverse sectional view taken on the broken line II—II, Fig. 1; Fig. 3 a view of the parts indicated in Fig. 1, the outer end of the journal box being partially turned upwardly 70 in the operation of the removal of the journal bearing; Fig. 4 a view similar to Fig. 3 showing the journal box being fully turned upwardly to permit the removal of the journal bearing, such bearing being indicated as having its outer end elevated prior to its removal; Fig. 5 a side view of the parts in the positions indicated in Fig. 4, the bearing having been removed; Fig. 6 a perspective view of the journal bearing 75 illustrated in Figs. 1, 2 and 3; Fig. 7 a view similar to Fig. 1 showing a standard journal bearing as having replaced the journal bearing of Fig. 6; Fig. 8 a view similar to Fig. 2 showing the standard bearing of Fig. 7 80 in place of the bearing of Fig. 6.

In the practice of the invention there is placed between the axle journal and the journal box a journal bearing having end thrust faces substantially semi-circular in 100 form and extent. In other words, the lower edges of the thrust bearing faces extend downwardly to, or substantially to, a horizontal plane passing through the axis of the axle. The lower wall of the journal box is 105 spaced away from the outer end of the axle to permit the outer end of the box to be turned upwardly at such angle to the axle

2
that the outer end of the journal bearing may be sufficiently elevated to have its lower edges clear the outer flange of the axle. The truck frame and journal box are provided 5 with means preferably in the form of cooperating lugs to limit the upward turning of the outer end of the box and to render the further application of lifting force upon the outer end of the box effective to raise 10 the box bodily in parallel relation with its extreme inclined position.

In the illustrative embodiment of the invention there is indicated a car axle 1 provided with a journal 2 having end flanges 3 15 and 4 forming end thrust bearing faces, all of which may be of standard or any desired construction. Upon the journal 1, there is mounted a journal bearing 5, which supports the journal box 6, upon which in 20 turn the end of the truck side frame 7 rests.

While, as far as some features of the invention are concerned, the journal bearing 5 may be variously formed, it is preferred to use a bearing of the form particularly illustrated in Fig. 6. This bearing 25 has end thrust faces 8 and 9 which are semi-circular in form and extent to give a maximum area of bearing surface against the journal flanges 3 and 4 and at the same time 30 permit the bearing to be applied laterally to the journal. The interior journal-bearing face of the block is of usual form, being a portion of a cylinder. The exterior box-bearing portion of the block preferably 35 comprises a central horizontal face 10, and, at each side thereof, inclined faces 11 extending downwardly and outwardly from the horizontal face. The faces 10 and 11 preferably lie in the same plane as the corresponding 40 faces of the standard journal bearing so that in service, should occasion arise to do so, a standard journal bearing may replace the bearing of Fig. 6. Rather than having the horizontal face 10 and the 45 inclined faces 11 extend continuously from end to end of the bearing, these faces are interrupted by grooves 12, thus effecting a substantial saving in the metal required to form the bearing. To properly retain the 50 bearing in the journal box, it is provided with lugs 13 adapted to extend laterally into pockets 14 formed in the journal box, as seen in Fig. 3. The front end of the bearing may be provided with lugs 15 serving 55 the double purpose of preventing the bearing from being placed wrong end foremost in a box, and for engaging the bearing both for removing it from, and placing it in, the journal box. With respect to the placing 60 of the bearing in a box, it will be understood that the end fillets of the journal are of substantially different radii, and that to have the bearing properly rest upon the journal its corresponding rounded edges 65 must conform to the fillets. Between the

ends of the bearing, its lower edges may be recessed as at 16 to effect a further saving in the amount of metal required to construct the bearing. Such recessing of the edges of the box forms, in effect, end legs 70 upon the bearing. As seen in Fig. 2 these legs preferably do not conform neatly to the journal but are spaced slightly from it.

The journal box 6 may be of standard form with the exception that its lower wall 75 is spaced from the journal to an extent sufficient to permit the outer end of the box to be turned upwardly to the final position indicated in Fig. 4. This is preferably effected by forming a depression 17 in the 80 lower outer end of the box, such construction permitting the major portion of the lower wall of the box to form a grease well sufficiently close to the journal to adequately lubricate it.

As seen in Figs. 2 and 8, the outer face 85 of this well-forming part of the box is preferably flattened to form a jacking pad to receive a jack when it is desired to turn the outer end of the box upwardly. The interior of the upper wall of the box is provided with a horizontal bearing face 18 and with adjoining inclined bearing faces 19 which rest upon the bearing faces 10 and 11 of the journal bearing. The box may be 90 further provided with a dust ring holder 20, lugs 21 for the attachment of a lid, and a recess 22 to receive the end lug 32 found on standard journal bearings, all of which 95 parts are of familiar construction.

As previously stated, the journal box and truck frame may be provided with cooperating lugs for limiting the upward turning of the box. Preferably, each side face of the box is provided with a laterally extending 105 lug 23 of the general wedge-shape indicated in Fig. 5, and the truck frame 7 with two pairs of lugs 24 and 25, the members of each pair being arranged one on each side of a box lug 23 and spaced from the sides of 110 such lug. Pins 26 and 27 may extend, respectively, through the pairs of lugs 24 and 25 below the box lugs 23 so that when the truck frame is elevated by a crane or otherwise, the car axles may also be lifted. The 115 upper central portion of the journal box may be provided with a rib 28 adapted to be received by a groove 29 formed on the lower face of side frame 7.

When it becomes necessary or desirable 120 to remove and replace a journal bearing, the outer end of the journal box is turned upwardly. This may be done by means of a jack placed below the journal box and operating on the flattened portion thereof substantially in the direction indicated by the arrow 30 in Fig. 3. When the box has 125 been so turned that its longitudinal axis is inclined to that of the axle substantially to the extent indicated in Fig. 3 the box 130

lugs 23 are brought into contact with the outer members of the pairs of frame lugs 24 and 25 so that further upward lifting force applied to the outer end of the journal 5 box causes such box as a whole to move upwardly from its position shown in Fig. 3 to that shown in Fig. 4 so that the rear end of the box is above and out of contact with the rear end of the journal bearing. 10 The journal bearing may then be engaged by its lugs 15, its outer end lifted so that the lower edges of its thrust bearing face 8 are above the periphery of flange 3 as 15 seen in Fig. 4, and the block moved outwardly through the journal box opening. With the box in the position indicated in Fig. 4, a new bearing may be placed upon the journal, and such new bearing 20 may be either of the form shown particularly in Fig. 6, or it may be a standard bearing 31, the form of which is shown in Figs. 7 and 8. Thus, the special bearing, constructed to have much longer life 25 than the standard bearing and to have other advantages explained above, may be replaced either by another special bearing of the same type, or, if such special bearing is not available it may be replaced by a standard bearing, a supply of which is usually readily 30 available. If a standard bearing is used, its inner lug 32 may engage the recess 22 formed in the inner end of the journal box, and its outer end lugs 33 may engage box lugs 34 to retain the bearing in place.

35 From the foregoing it will readily be seen that, in the practice of the invention, journal bearings having greatly enlarged end thrust bearing faces may be used with the result that the life of the bearing is 40 very substantially prolonged, and this without additional cost of construction. It will furthermore be seen that the bearing may be readily removed and replaced either by a similar bearing, or by a standard bearing 45 having much smaller end thrust faces.

According to the provisions of the patent statutes, I have described the principle and operation of my invention together with the construction which I now consider to 50 represent the best embodiment thereof. However, I desire to have it understood that, within the scope of the appended claims, the invention may be practiced with other forms of construction than that specifically shown and described.

55 I claim as my invention:

1. In a railway truck, the combination of 60 an axle provided with a journal having at its end a flange forming a thrust bearing face, a bearing mounted upon the journal and having a substantially semi-circular end face cooperating with said thrust bearing face, and a journal box enclosing said journal and bearing and having the outer portion of its lower wall spaced from the jour-

nal to permit the outer end of the box to be turned upwardly to an extent sufficient for the removal of said bearing.

2. In a railway truck, the combination of 70 an axle provided with a journal having flanges forming end thrust bearing faces, a bearing mounted upon the journal and having substantially semi-circular end faces cooperating with said thrust bearing faces, and a journal box enclosing said journal and bearing and having a depression at its lower outer end to permit the outer end of the box to be turned upwardly at a sufficient angle to the axle for the removal of said bearing. 75

3. In a railway truck, the combination of 80 an axle provided with a journal having flanges forming end thrust bearing faces, a bearing mounted upon the journal and having substantial semi-circular end faces 85 cooperating with said thrust bearing faces, a journal box enclosing said journal and bearing and having a depression at its lower outer end to permit the outer end of the box to be turned upwardly at an angle 90 to the axle sufficient for the removal of said bearing, and a truck frame supported by said box, said frame and box being provided with cooperating lugs for limiting said upward turning of the box. 95

4. In a railway truck, the combination of 100 an axle provided with a journal having at its end a flange forming a thrust bearing face, a bearing mounted upon the journal and having a substantially semi-circular end face 105 cooperating with said thrust bearing face, a journal box enclosing said journal and bearing and having its lower wall spaced from the journal to permit the outer end of the box to be turned upwardly for the removal of said bearing, and a truck frame supported by said box, said frame and box being provided with cooperating lugs for 110 limiting the upward turning of the box whereby the box is caused to move bodily upwardly in its inclined position to the axle upon further upward movement of the outer end of the box after said lugs have been brought into engagement with each other.

5. In a railway truck, the combination of 115 an axle provided with a journal having flanges forming end thrust bearing faces, a bearing mounted upon the journal and having substantially semi-circular end faces 120 cooperating with said thrust bearing faces, a journal box enclosing said journal and bearing and having its lower wall spaced from the journal to permit the outer end of the box to be turned upwardly for the removal of said bearing, and a truck frame supported by said box, the exterior face of each side of said box being provided with an outwardly extending lug, and said truck frame being provided with two pairs of lugs, the elements of said pairs of lugs lying 125 130

on opposite sides of said box lugs and being spaced therefrom for limiting the upward turning of said box whereby the box is caused to move bodily upwardly upon further application of lifting force when the limit of its turning movement has been reached.

6. In a railway truck the combination of an axle provided with a journal having end flanges forming thrust bearing faces, a bearing mounted on the journal, a journal box enclosing said journal and bearing and having its lower wall spaced from the journal to permit the outer end of the box to be turned upwardly for the removal of said bearing, and a truck frame supported by said box, said frame and box being provided with cooperating elements for limiting said upward turning of the box.

7. In a railway truck, the combination of an axle provided with a journal having flanges forming end thrust bearing faces, a bearing mounted upon the journal and having substantially semi-circular end faces co-operating with said thrust bearing faces, said bearing being provided with laterally extending retaining lugs intermediate its ends, a journal box enclosing said journal and bearing and having a depression at its lower outer end to permit the outer end of the box to be turned upwardly at an angle to the axle for the removal of said bearing, the side walls of said box being provided with pockets to receive said bearing retaining lugs, and a truck frame supported by said box, said frame and box being provided with cooperating lugs for limiting said upward turning of the box.

8. In a railway truck, the combination of an axle provided with a journal having a flange at its outer end, a bearing mounted on the journal, and a journal box enclosing said journal and bearing and mounted to have its outer end elevated to remove the bearing, said box having a depression in its lower outer portion to receive said journal flange when the outer end of the box is elevated.

9. In a railway truck, the combination of an axle provided with a journal having a flange at its outer end, a bearing mounted on

the journal, and a journal box enclosing said journal and bearing and mounted to have its outer end elevated to receive the bearing, said box having a depression in its lower outer portion forming a lubricant well and capable of receiving said journal flange when the outer end of the box is elevated, the outer face of the depression-forming part of the box being flattened to form a jacking pad.

10. In a railway truck, the combination of an axle provided with a journal having an end flange, a bearing mounted on the journal, a journal box enclosing said journal and bearing and having its lower wall spaced from the journal to permit the outer end of the box to be turned upwardly for the removal of said bearing, each side of the box being provided with an outwardly-extending lug, and a truck frame supported by said box and provided with lugs arranged on opposite sides of said box lugs, said frame and box lugs cooperating to limit said upward turning of the box.

11. A railway car truck journal box having the bottom formed at an angle with the inside of the top of the box so that the normal jack face brought against the bottom of the said box in lifting same will bring it to the proper angular position for removing or inserting the bearing.

12. A railway car truck journal box having the outside of the bottom formed at an angle with the inside of the top wall so that the normal face jack brought against the bottom of the box in lifting same will cause it to rotate to the necessary angle to allow the removal and insertion of the bearing.

13. A railway car truck journal box having the outside of the bottom wall formed at an angle with the inside of the top wall so that the normal face jack brought against the bottom of the box in lifting same will cause it to rotate to the necessary angle to allow the removal and insertion of the bearing.

In testimony whereof, I sign my name.

EDGAR W. SUMMERS.

Witness:

EDWIN O. JOHNS.
